AIR COOLER

Albert H. Massey, El Paso, Tex.

Application March 18, 1940, Serial No. 324,715

1 Claim. (Cl. 261—30)

The invention relates to an air cooler and more especially to an air conditioning apparatus.

The primary object of the invention is the provision of an apparatus of this character wherein air within an enclosure will be cool and humidified by the operation of such apparatus, dust and foreign matter will be removed from the air concurrently with the cooling and humidifying operation of the said machine.

Another object of the invention is the provision of an apparatus of this character wherein the construction thereof is novel in its entirety and such apparatus is susceptible of being moved from one locality to another, being compact and is an operative unit independent of house heating and cooling systems generally employed.

A further object of the invention is the provision of an apparatus of this character wherein the temperature within an enclosure can be varied and the air within circulated while such air will be cooled and moistened as well as cleaned during the working of the apparatus.

A still further object of the invention is the provision of an apparatus of this character, which is simple in its construction, thoroughly reliable and efficacious in operation, economic in the working thereof, of a size to occupy the least possible space, being readily portable for the moving thereof from place to place within an enclosure, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention and pointed out in the claims hereunto appended.

In the accompanying drawings:

Figure 1 is a front elevation of the apparatus constructed in accordance with the invention.

Figure 2 is a sectional view taken on the line 2—2 of Figure 3 looking in the direction of the arrow.

Figure 3 is a sectional view taken on the line 3—3 of Figure 1 looking in the direction of the arrow.

Figure 4 is a sectional view taken on the line 4—4 of Figure 1 looking in the direction of the arrow.

Figure 5 is a fragmentary detail vertical sectional view showing a float control for use in the apparatus.

Similar reference characters indicate corresponding parts throughout the several views in the drawings.

Referring to the drawings in detail, the apparatus constituting the present invention comprises a box-like body 10 in the form of a sheet metal casing of the required size and having at its bottom casters or rollers 11, being of the swiveled fixture type, and the open top of this body 10 is closed by a removable lid or cover 12, which is marginally rimmed to telescopically fit over the said open top. Formed in the front and rear walls of the body 10 are wire mesh covered or screened air outlet and intake openings 12 and 13, respectively, each preferably of circular contour while the intake opening 13 is vertically off center with respect to the opening 12. The wire mesh coverings or screens for the openings 12 and 13 are denoted at 14.

Within the body 10 crosswise of the interior space thereof are the horizontally arranged supports 15 and 16, respectively. The latter support in its horizontal position is fixed to the rear wall 23 of the said body 10. The support 15 of board form is fixed to wall brackets 17, these being secured to the front wall of the body 10, and the said support 15 in its horizontal position creates a shelf on which is fixedly held the casing 18 of an electric motor. The power shaft 19 of the motor carries a bladed fan wheel 20. The fan wheel 20 is in close relation to the outlet opening 12 and surrounding this wheel is an unbroken annular flange 21 indent from the front wall of the casing 10 entirely about the opening 12.

The shelf created by the support 15 carries a bearing 22 for the axle 23 of a perforated cylinder 24, the axle 23 being also journaled in the support 16. The cylinder 24 rotates on a horizontal axis, the axle 23 being the horizontal axis for the rotation of the said cylinder. The end of the cylinder 24 next to but spaced from the rear wall of the casing 10 is completely closed at 25 while the other end of this cylinder adjacent to the front wall of the casing 10 is completely open. The axle 23 for the cylinder 24 and the latter are joined by spokes 26, these being of a kind of eliminate the retarding of the flow of air from within the cylinder 24 through the outlet opening 12 to the exterior of the casing 10.

The cylinder 24 at opposite ends thereof is externally flanged at 27 and these end flanges are continuous about the periphery at the outer side of the cylinder 24 while covering the exterior surface of the cylinder 24 between the flanges 27 is a filtering body 28 of absorbent characteristic. The body 28 extends entirely about the cylinder 24 throughout the outer periph-

ery thereof and is held confined between the flanges 27 in any desirable manner.

Adapted to flow into the casing 10, preferably to a level as at 29, is a quantity of water 30, the depth thereof being such when within the body 10 to wet the filtering material 28 on the rotation of the cylinder 24. The axle 23 of this cylinder has fixed thereto a belt wheel 31, having trained thereover an endless belt 32, which is also trained over a belt pulley 33. This pulley 33 is fixed to a driven shaft 34 carrying a belt wheel 35 over which is trained an endless belt 36. The belt 36 is trained over a pulley 37 fixed to the power shaft 19 of the electric motor and the latter furnishes the power for the rotation of the cylinder 24. The arrangement of the belt pulleys, belts and belt wheels between the motor 18 and the cylinder 24 regulates the speed of rotation of the said cylinder.

Arranged within the casing 10 elevated with respect to the cylinder 24 is a water supply tank 38 having a delivery port controlled by a valve 39, its stem 40 being pivoted at 41 to the rocker arm 42 for a ball float 43. The arm 42 is swingingly carried by a bracket 44 secured to one side wall of the casing 10 a determined distance above the bottom of the said casing 10 so that the float 43 will be affected by the quantity of water 30 within the casing 10. On the lowering of the quantity of water 30 in the lower portion of the casing 10, the valve 39 becomes operated by the float 43 and on opening of such valve the water within the tank 38 will drop through gravity to the bottom of the casing 10 for the bringing of the quantity of water to a determined level within said casing resulting in the closing of the valve 39 to shut off further water supply from the tank 38. The air within a room is caused to be circulated for the operation of the fan wheel.

In the operation of the apparatus, the air within an enclosure is admitted through the intake opening 13 at the rear of the casing 10 to the interior of the latter and by the action of the fan wheel 20 this air will be drawn through the filtering medium 28 when circulating exteriorly about the cylinder 24 when rotating and such air becomes filtered when drawn within the cylinder whence the fan wheel discharges the air from said cylinder through the front opening 12 back into the room. This circulation of the air undergoes treatment for the cooling thereof, cleaning and also will be humidified so that such air will be thoroughly conditioned within the apparatus when operating upon return of the air to the enclosure after being taken therefrom into the said apparatus.

The tank 38 is filled with a quantity of water on removing the cover 12 from the casing 10.

The cylinder 24 is rotated at a determined speed of rotation, preferably being rotated slowly, and in this manner the air will be thoroughly cleaned, humidified and cooled to the required temperature.

The shelf constituted by the support 15 carries a bearing 45 for the stud shaft 34 provided with the pulley and belt wheel 33 and 35, respectively, over which are trained the belts hereinbefore mentioned.

When the cylinder 24 is continuously rotated, the water 30 within the lowered portion of the casing 10 moistens or wets the filtering medium 28 peripherally about the cylinder 24 and in this way dust or other foreign matter will be collected by said filtering medium for the removal thereof from the air when passing through the apparatus and air conditioned thereby.

The cylinder 24 extends a distance in close relation to the front and rear walls of the casing 10 and the front open end of this cylinder incases the motor, the belts, the belt wheels and pulleys under the arrangement thereof as hereinbefore set forth.

The quantity of water within the lower portion of the casing 10 is maintained at a determined level through the operation of the float 43 and the valve 39 controlled thereby.

What is claimed is:

An apparatus of the kind described comprising a casing open at opposed sides forming a water container and having a removable top cover, horizontally arranged supports interiorly of the casing at the openings in opposite sides thereof, one of said supports being a shelf and having bearings, a foraminous cylinder within said casing and having a central axle journaled in one of the bearings and the other support, the said cylinder being closed at one end and open at the other end, a filtering body applied exteriorly about said cylinder, external end flanges on the cylinder and holding the filtering body in place upon said cylinder, a belt wheel fixed to the axle of said cylinder next to the shelf, a power unit carried by said shelf and having driving connections fitting the other bearing and engaging said belt pulley for transferring power from the power unit to the said axle, a fan within one of said openings in the casing and having driven connections with the said power unit, a water tank arranged within the casing above the cylinder and having an outlet communicative with said cylinder, and a float controlled valve within the casing and operated by water within the lower portion thereof for the opening and closing of the outlet in said tank, the said cylinder and fan being aligned with each other.

ALBERT H. MASSEY.
